UNITED STATES PATENT OFFICE

JOHN WESLEY BELL, OF KENDAL, SASKATCHEWAN, CANADA

BEATER OR MIXER

Application filed September 16, 1929. Serial No. 393,012.

This present invention relates to new and useful improvements in a beater or mixer and has for its primary object the provision of a simple and inexpensive structure whereby two or more mixtures may be beaten or mixed in separate containers with one operation of the device.

Another object of the invention resides in the provision of a beater or mixer of the character stated in which each beater or mixer proper is composed of oppositely rotating agitators having alternating or interlocking agitator fingers.

A further object of the invention resides in the provision of a beater or mixer of the character stated in which twin beaters or agitators proper are supported in parallel spaced relation and operated from the same operating shaft with a single control means.

A still further object of the invention resides in the provision of a beater or mixer of the character stated in which all of the operative parts are enclosed in a single casting with removable caps or heads at the open extensions thereof to protect all of the operative parts from dust and the like.

A still further object of the invention resides in the provision of a beater or mixer of the character stated which is of such construction that by operation of the control plunger the operating shaft will be rotated to drive in opposite directions the cooperating agitator members of the twin beaters proper to mix the contents of separate containers with the one operation of the device.

A still further object of the invention resides in the provision of a beater or mixer of the character stated which is composed of the minimum number of parts, of simple construction and operation and the complete structure being such that the device may be produced and assembled at the minimum cost.

To the accomplishment of these and related objects, as shall become apparent as the description proceeds, my invention resides in the construction combination and arrangement of parts as shall be hereinafter more fully described, illustrated in the accompany-

ing drawings and pointed out in the claims hereunto appended.

The invention will be best understood and can be more clearly described, when reference is had to the drawings forming a part of this disclosure, wherein like characters indicate like parts throughout the several views.

In the drawings:

Figure 1 is an elevation of the improved beater or mixer;

Figure 2 is a vertical section through the same; and

Figure 3 is a transverse section, substantially on the plane of line 3-3 of Figure 2, looking in the direction indicated by the arrows.

Referring more in detail to the drawings, it is to be noted that the complete device may be supported on the stem 6 having the foot 7 formed on its lower end. The stem 6 has its upper end slidably mounted in the tube 8 and having its movement longitudinally thereof limited by the stop pin 9 extending transversely through the stem 6 and working in the elongated slot 10 in opposite sides of the tube 8. The stem 6 is resiliently held in its lowermost position by the spring 11 within the upper end of the tube 8 and pressing on the upper extremity of the stem 6. The tube 11 has its upper end threaded in the depending central portion 12 of the casting 13 in the horizontal portion of which is rotatably mounted the operating shaft 14. Appropriate bearings 15 are provided in the casting 13 for the shaft 14 and the latter has collars 16 provided thereon on opposite sides of the bearing 15 to prevent longitudinal movement of the shaft 14 in the casting 12. The central crank portion 17 of the shaft 14 has connected thereto the link 18 which also pivots to the forked or bifurcated lower end 19 of the control plunger 20. The link 18 and control plunger 20 work in the upstanding portion 21 of the casting 13 and said plunger 20 operates through the upper end thereof with a head 22 or knob on its upper extremity. An extension spring 23 is located between the head or knob 22 and the upper end of the upstanding portion 21.

100

of the casting 13 to resiliently retain the control plunger 20 in its normal uppermost or unoperated position.

Carried on each end of the shaft 14 is a large bevelled gear 24 which operates in opposite directions a small upper bevelled gear 25 and a corresponding lower bevelled gear 26. The bevelled gear 24 and the bevelled gears 25 and 26 are enclosed in an enlarged extension 27 of the casting 13 at either end 10 of the horizontal portion thereof. The bevelled gear 25 is rigid on the shaft 28, near the upper end thereof while the bevelled gear 26 is rigid with the sleeve 29 which is loose 15 on the shaft 28. The shaft 28 extends vertically through the enlarged extension 27 and is rotatable in appropriate bearings 30 in the extension 27 and the outer closure plates 27a thereof. The shaft 28 has pairs of spaced 20 radial mixer blades or agitator fingers 31 on its lower end, the uppermost and lowermost blades or fingers 31 being of uniform length and slightly shorter than the intermediate blades or fingers 31. The free ends of all the 25 blades or fingers 31 are bevelled to describe an arc. Working between the blades or fingers 31 are the inwardly directed blades or fingers 32 which are carried on the opposite opposed branches of the oval frame 33, the 30 converged upper ends 34 of which are carried in the cross-head 35 on the lower end of the sleeve 29, below the extension 27 of the casting 13. The lower end of the frame 33 is secured on the lower extremity of the shaft 35 28.

The construction of the beater or agitator is duplicated on the two sides or halves of the beater or mixer structure and therefore does not require further detailed description.

40 The casting 31 with its extensions 27 and up-standing portion 21 may be suitably divided into two or more sections to permit of easy assembling of the casting parts and mounting of the operative parts within the casting, 45 or removal of the operative parts, or inspection or repair thereof, at small cost and the minimum expenditure of time and labour.

As the construction of the device has thus been described in detail, brief reference is 50 now had to its use and modus operandi: The beater or mixer may be employed for beating or mixing the contents of two separate containers simultaneously or in a single container, if desired. In the latter case, the 55 device will be supported entirely within the container by the foot 7 resting therein. In the former case, the foot 7 would rest on the stationary support between the two containers and on which the latter may also rest. 60 In either case the two beater structures are simultaneously operated by the single operating shaft simply by pressing repeatedly on the head or knob 22. This operation assures opposite rotation of the blades or fingers 31 and the co-operating blades or fingers

32 of each beater or mixer structure thus assuring thorough agitation of the contents of the vessel or vessels, as the case may be.

From the foregoing description taken in connection with the accompanying drawings, it will be manifest that a beater or mixer is provided that will fulfill all the necessary requirements of such a device, but as many changes could be made in the above description and many apparently widely different 70 embodiments of my invention may be constructed within the scope of the appended claims without departing from the spirit or scope thereof, it is intended that all matters contained in the said accompanying specification and drawings shall be interpreted as 75 illustrative and not in a limited sense.

Having thus described my invention, what I claim as new and desire to secure by Letters Patent is:

1. A device of the class described including a transverse shaft having a central crank portion; gear wheels mounted on the opposite ends of said shaft; double beater members arranged outwardly of said gear wheels and driven thereby; reciprocating driving means extending upwardly from said shaft and connected with the central crank portion thereof; enclosing and supporting means for said shaft, the gears carried thereby, the double beater members and the central driving means for said shaft; a resilient central support for said last mentioned means; and means to resiliently retain in normal unoperated position the central driving means 100 for the said shaft.

2. A device of the class described including a horizontal crank shaft having a central crank portion; large gears mounted on the opposite ends of said crank shaft; a casing for said crank shaft and said large gears with an upstanding central portion; a reciprocating operating member in the upstanding portion of said casing; a link connection between said reciprocating operating member and the central crank portion of said crank shaft to drive the latter; means to resiliently retain said reciprocating driving member in its uppermost position; a resilient support depending from the centre of said casing; a double beater member supported in the outer ends of said casing outwardly of said large gears; small gears for said double beater members meshing with said large gears; and removable means for closing 110 the outer ends of said casing.

In testimony whereof I hereunto affix my signature.

JOHN WESLEY BELL. [L.S.]
